GRINDING MACHINE

Raymond H. Cramer, Newark, N. J., assignor to
General Motors Corporation, Detroit, Mich., a
corporation of Delaware

Original application July 30, 1940, Serial No.
348,398, now Patent No. 2,311,213, dated Febru-
ary 16, 1943. Divided and this application April
30, 1942, Serial No. 441,163

12 Claims. (Cl. 51—105)

This invention relates to grinding machines and comprises all of the features of novelty herein disclosed. An object of the invention is to provide improved means for controlling the relative feeding movement between an abrading member and a work piece. Another object is to provide suitable slides for supporting, guiding and adjusting into position the member which is fed, the member fed being herein shown as the grinding wheel. Another object is to provide an improved feed mechanism wherein the grinding wheel or other fed member is brought rapidly towards the co-operating member, as by a piston and cylinder unit, and is then fed slowly under control of a cam and a cam follower one of which is turned by a second piston and cylinder unit of the rotary vane type connected to the first unit. This application is a division of my copending application Serial Number 348,298, which matured as Patent No. 2,311,213, Feb. 16, 1943.

In the drawings

Fig. 1 is chiefly a vertical section of the work head with wheel feeding mechanism shown in front elevation.

Fig. 2 is a left end view of the compensating mechanism.

Fig. 3 is a front view of the compensating slide and the wheel slides mounted thereon, the slides being in a different position from that of Fig. 1.

Fig. 4 is a side view and Fig. 5 is a sectional view of said wheel slides.

Fig. 6 is an exploded view of parts appearing in Fig. 3.

Fig. 7 is a sectional view of the two cylinders which control the wheel slide.

Fig. 8 is an enlarged cross sectional view of the short cylinder of Fig. 7.

Fig. 9 is a sectional view of the needle valve in the region of line 14 of Fig. 8.

Fig. 10 is a sectional view of the check valve in the region of line 15 of Fig. 8.

Fig. 11 is a perspective view of the cam of Fig. 7 and associated parts.

This machine grinds an overhanging flange or conical shoulder 4 at the end of a tapered raceway 2 on the inner race ring 6 of a tapered roller bearing. There is a rib 8 at the small end of the ring and a relief groove 10 at each end of the raceway. The race ring is rotated by a work holder or chuck C on a work head H. The flange or shoulder is ground by a conical surface 12 at the conical edge of a tapering flange on a grinding wheel F which is dished and has its drive shaft supported in a slanting position above the

work. This wheel is mounted on the work head and is fed downwardly at a small angle to the shoulder. There is a means to compensate for wheel wear and an adjustment of the angle of feed. The grinding wheel F has a preliminary quick advance controlled by a piston and cylinder unit to a position ready to grind. Subsequent slow feed is controlled by a rotary cam operated by a vane in a short cylinder which has a needle valve and a check valve.

The work head H comprises a housing 20 in which a hollow spindle 22 is journalled for rotation by bearing sleeves 24 and 26 having bearing inserts 28 and 30. Endwise movement of the spindle is prevented by a pair of preloaded ball bearings 32 arranged back to back, the inner race rings being clamped on the spindle by a nut 34 and the outer race rings being clamped between a flanged bearing housing 36 and a dished cap 38 having a seal 40. The spindle is driven by a wide belt pulley 42 enclosed within a guard 44. The pulley is made wide to provide for axial adjustment of the work head with respect to its driving means. At the chuck end the spindle is protected by a double seal 46 and the spindle has a flange carrying a water slinger 48. The work is clamped to the chuck by clamping fingers 68 operated by a suitably operated draw rod 62 extending through the hollow spindle. The wide pulley 42 is driven by a belt 130 running past a take-up idler pulley 132 mounted on a spring pressed arm 134, the belt running around a pulley 136 on a shaft 138 journalled in a housing 140 on a plate 142 having a hollow trunnion 144 through which a suitable drive extends to a spiral gear 150 on the shaft 138. The plate 142 can be oscillated for some purposes but for present purposes is swung to a selected angular position and clamped by a bolt 146 passing through a slot 148 to a main frame. The housing 140 has a raised portion 156 with a dovetail tongue 158 on which the work head H is adapted for horizontal adjustment as by means of a screw 160 threaded in a nut 162 and journalled for rotation in a bracket 164 on the work head. An ejector E, in the form of a pivoted fork embracing the chuck next to the work, is secured to a rock shaft 168 rockably supported by a forked bracket 170. An arm 172 is pinned to the rear end of the shaft and is connected by a loose pivot 174 to an actuating bar 176 operated by a pull solenoid 184.

On the top of the work head is a dovetail tongue 194 on a plate 196 to guide a compensating slide 198 which is adjusted by a screw 200

threaded in a nut 202 and journalled for rotation without endwise movement in an angle bracket 204 having one leg fastened at the end of the plate 196. The feed screw has a knob 206 for manual operation and is keyed to a ratchet wheel 208 for automatic adjustment. Swinging on the hub of the ratchet wheel is a lever 210 carrying a pawl 212. A coil spring 214 urges the lever in one direction to bring an adjustable stop screw 216 against a face on the bracket 204, this screw adjusting the stroke of the pawl. The end of the lever is connected by a link to a plunger 218 on a pull solenoid 220 mounted on the other leg of the bracket 204. Wires leading to the solenoid are mounted on a clamp 222. The solenoid is suitably actuated at every machine cycle as in the parent application to feed the compensating slide 198 to the left to compensate for wear and dressing of the wheel F.

The compensating slide has an upstanding web 224 which supports a swivel plate 226 having ways for guiding a slide which adjusts the grinding wheel F up or down towards or from the work, the angle or direction of feed being adjustable also. Pressed into a hole in the web 224 is a pivot pin 227 which pivotally supports the swivel plate 226 by entering a hole therein. The web 224 also has arcuate slots 228 through which clamping bolts 230 are passed into tapped holes in the swivel plate, one tapped hole being in a side lug 232 on the swivel plate and the other at the center line. The swivel plate has a dovetail tongue 234 on the front to fit a dovetail way in a slide 236, the slide being adjustable manually up and down by a screw 238 threaded in a tapped hole in the swivel plate and journalled for rotation without endwise movement in a lug 240 on the rear of the slide at the top. This is a preliminary or set-up manual adjustment and another slide or block on the slide 236 feeds the wheel F towards or from the work automatically.

The front face of the slide 236 has bolted thereto a fixed gib 242 having a V-shaped slideway mating with a similar slideway on a gib 244 which is adjustable by screws 246 threaded in side lugs 248 on the slide. The mating ways form a slideway for a feed block or slide 250 which is bolted to the rear or bottom face of an angular extension 252 on a sliding spindle housing 254 in which the slanting drive shaft of the grinding wheel F is journalled by any suitable bearings. The shaft has a wide pulley 255 driven by a belt from a suitable motor. The angular extension is secured to the end of a piston rod 256 which passes freely through a hole in a flange 258 at the upper end of the slide 236, the piston rod being connected to a piston in a cylinder 260 which is bolted to the upper face of the flange 258. The spindle housing and its extension together with the attached block 250 form a feed slide which is rapidly fed towards the work ready to begin grinding, this slide afterwards feeding forwardly very slowly under control of a cam which is rotated by a vane in a cylinder attached to the top of the cylinder 260 as will later appear.

The sliding return or upward movement of the grinding wheel is made to control a switch 262 having a plunger engaging a switch lever 264 and urging it towards a stop pin 266, the switch being secured by a bracket to the flange 258. The lever is pivoted on a pivot screw 270 between a thick spacer 272 and a thin spacer 274, these parts being held by lock nuts on the pivot screws.

The switch lever lies in the path of a dog 276 pivoted on a plate 278 and urged towards a stop pin 280 by a light coil spring 282. The plate has elongated slots and is adjustably secured by clamping screws 284 to a bracket on the angular extension 252. On the return or upward movement of the grinding wheel and its slide, the dog 276 will actuate the switch lever 264 and close the switch but upon the advance the dog will swing idly over the hooked end of the switch lever. This switch controls a solenoid, as explained in the parent application, and reverses a valve to actuate a dressing device, which dresses the wheel F along its conical operating face 12.

Piston and cylinder feed

The cylinder 260 has its upper head 290 of large diameter and forming the lower head of a short cylinder 292 having an upper head 294. The piston rod 256, including a detachable extension 256A which clamps against the piston, passes through both cylinders and through a sleeve 298 journalled in the cylinder heads and turning freely around the piston rod extension. A rockable piston or vane 298 is attached to the sleeve by screw bolts and is adapted to operate between stop screws 300 and 302 fastened to the ends of a segment 304 bolted to one cylinder head. When feeding the wheel forward, pressure fluid enters the cylinder 260 through a port 306 and enters the cylinder 292 through a branch port 308, port 308 coming in near the stop screw 300. Exhaust fluid leaves the cylinder 260 at a port 310 and leaves cylinder 292 through a small port 312 leading to a needle or throttle valve 314 which is adjustable by a hand wheel 316. Port 312 communicates past the needle valve with a longitudinal port 318 leading to a circumferential port 320 which comes into a longitudinal exhaust port 322 of large diameter. Movement of the vane or rockable piston 298 in one direction is thus very slow depending on the setting of the needle valve.

When the flow of fluid is reversed, the port 322 becomes the entrance port and port 308 becomes the exhaust port. The entrance port 322 leads through a ball seat 324 to lift a ball check valve 326 towards a loose stop pin 328 and permit the pressure fluid to enter the cylinder rapidly through a port 330. Thus the vane will return rapidly. In the slow advance, the ball check valve is of course seated to prevent exhaust of fluid therethrough and to compel the fluid to pass through ports 312 and 320 and the interposed needle valve.

The extension 256A of the piston rod 256 is threaded at the end to receive a nut 332 holding a block 334 having trunnions for a pair of cam follower rollers 336 adapted to engage an annular cam 338. The cam body is connected by clutch teeth 339 to the end of the sleeve 298 and bears against a ball thrust bearing 340 inside a guard 342. The rollers are initially separated from the cam but descend rapidly with the piston rod until stopped by the cam, the small and devious passages in the short cylinder 292 being inactive until the piston rod is stopped. Thereafter the pressure will build up and cause the fluid to exhaust through the restricted passages and thereby control a slow rotation of the vane and the cam. Thus there is a rapid movement of the grinding wheel towards the work with a slow feed for actual grinding. The cam has a low portion and a little rise providing a dwell and a slight preliminary retraction at the

conclusion of grinding. When the flow of pressure fluid is reversed, it is apparent that the piston rod 256 has control and hence the wheel will rapidly rise or return to its initial position, the cam rolls 338 moving away from the cam.

I claim:

1. In a grinding machine, a grinding wheel, a feed slide supporting the grinding wheel, a piston and cylinder unit having a piston rod connected to the feed slide, a second cylinder having a rotary vane, a cam connected to the vane, a cam follower on the piston rod, and means for causing fluid pressure to successively actuate the piston and the vane to produce a rapid initial movement of the feed slide followed by a slow feed under control of the cam.

2. In a grinding machine, a grinding wheel, a feed slide supporting the grinding wheel, a piston and cylinder unit having a piston rod connected to the feed slide, a second cylinder having a rotary vane, a cam connected to the vane, a cam follower on the piston rod, and means for causing fluid pressure to successively actuate the piston and the vane to produce a rapid initial movement of the feed slide followed by a slow feed under control of the cam, said means including wide open passages communicating with the piston and a restricted passage communicating with the vane.

3. In a grinding machine, a grinding wheel, a feed slide supporting the grinding wheel, a piston and cylinder unit having a piston rod connected to the feed slide, a second cylinder having a rotary vane, a cam connected to the vane, a cam follower on the piston rod, and means for causing fluid pressure to successively actuate the piston and the vane to produce a rapid initial movement of the feed slide followed by a slow feed under control of the cam, said means including wide open passages communicating with the piston and a needle valve interposed in a passage communicating with the vane.

4. In a grinding machine, a grinding wheel, a feed slide supporting the grinding wheel, a piston and cylinder unit having a piston rod connected to the feed slide, a second cylinder having a rotary vane, a cam connected to the vane, a cam follower on the piston rod, and means for causing fluid pressure to effect a rapid initial movement of the feed slide followed by a slow feed under control of the cam in one direction and a rapid retreat without slow movement in the opposite direction, said means comprising a needle valve and a check valve in the passages leading to the vane.

5. In a grinding machine, a grinding wheel, a feed slide supporting the grinding wheel, a piston and cylinder unit having a piston rod connected to the feed slide, a second cylinder mounted upon the first and having a rotary vane, a cam connected to the vane, the piston rod passing through both cylinders and having a cam follower normally spaced from the cam, and means for causing fluid pressure to successively actuate the piston rod to bring the cam follower against the cam and to turn the cam for controlling subsequent movement of the piston rod and the feed slide.

6. In a feed mechanism for controlling the relative feeding movement between a work piece and an abrading member, a slide, a piston and cylinder unit having a piston rod connected to the slide, a rockable member, an initially separated cam and a cam follower one of which is turned by the rockable member and the other

shifted by the piston rod, a second cylinder unit for turning the rockable member, fluid inlet and exhaust passages leading to the cylinders, one of the passages leading to the second cylinder

5 having a throttle valve whereby the piston rod brings the cam and the cam follower into contact at one speed and the rockable member controls further movement of the rod at a lower speed.

10 7. In a feed mechanism for controlling the relative feeding movement between a work piece and an abrading member, a slide, a rod connected to the slide, a rockable member turnable on the rod, an initially separated cam and a cam follower 15 one of which is connected to the rockable member and the other connected to the rod, means for urging the rod in a direction to bring the cam and the cam follower into contact, and means for thereafter turning the rockable member 20 to control further movement of the rod at a lower speed.

8. In a feed mechanism for controlling the relative feeding movement between a work piece and an abrading member, a slide, a rod connected to the slide, a rockable member turnable on the rod, an initially separated cam and a cam follower 25 one of which is connected to the rockable member and the other connected to the rod, means for urging the rod in a direction to bring the cam and the cam follower into contact, a cylinder and piston unit for turning the rockable member, fluid inlet and exhaust passages leading to the cylinder, and throttling means in one passage for postponing movement of the rockable member until said 30 contact occurs.

9. In a feed mechanism for controlling the relative feeding movement between a work piece and an abrading member, a slide, a rod connected to the slide, a rockable member turnable on the rod, 40 a cam and a cam follower one of which is connected to the rockable member and the other connected to the rod, a cylinder and piston unit for shifting the rod endwise in opposite directions, a second cylinder and piston unit for turning the 45 rockable member around the rod, fluid inlet and outlet passages leading to the cylinders, one passage having a portion common to both cylinders, and the other passage to the second cylinder having a throttle valve and a one-way check valve 50 to cause slower turning of the rockable member in one direction than the other.

10. In a feed mechanism for controlling the relative feeding movement between a work piece and a grinding wheel, a work head having a work 55 rotating spindle, a feed slide having means to rotatably support the grinding wheel, means for guiding said slide at an angle to the work spindle, said guiding means having a cylinder attached thereto, a piston rod projecting from the cylinder 60 to actuate the feed slide, a swivel plate supporting the guiding means, and a supporting member mounted on the work head and having a pivotal support for the swivel plate to provide for adjustment of the angle of feed.

65 11. In a feed mechanism for controlling the relative feeding movement between a work piece and a grinding wheel, a work head having a work rotating spindle, a feed slide having means to rotatably support the grinding wheel, means for 70 feeding the slide at an angle to the work spindle, a compensating slide mounted on the work head, means for shifting the compensating slide along the work head parallel to the work axis, a swivel plate pivoted to the compensating slide to adjust 75 the angle of approach of the work and the wheel,

said swivel plate having means mounted thereon to guide and support the feed slide.

12. In a feed mechanism for controlling the relative feeding movement between a work piece and a grinding wheel, a work head having a work rotating spindle, a compensating slide mounted on the work head, means for shifting the compensating slide along the work head parallel to the work axis, a swivel plate pivoted to the com-

pensating slide to adjust the angle of approach of the work and the wheel; a second slide guided by the swivel plate, means for adjusting the second slide on the swivel plate along said angle of approach, a feed slide guided by the second slide and having means to support the grinding wheel, and means supported by the second slide for shifting the feed slide thereon.

RAYMOND H. CRAMER.
